I. H. LEVIN

DIAPHRAGM FOR ELECTROLYTIC CELLS

Filed Oct. 4, 1921

Patented Apr. 15, 1924.

1,490,332

UNITED STATES PATENT OFFICE.

ISAAC H. LEVIN, OF NEW YORK, N. Y.

DIAPHRAGM FOR ELECTROLYTIC CELLS.

Application filed October 4, 1921. Serial No. 505,303.

To all whom it may concern:

Be it known that I, ISAAC H. LEVIN, a citizen of the United States, residing at the borough of Manhattan, in the city, county, 5 and State of New York, have invented certain new and useful Improvements in Diaphragms for Electrolytic Cells, of which the following is a specification, reference being had therein to the accompanying drawings, 10 which form a part thereof.

My invention relates to diaphragms for electrolytic cells, and more particularly to a diaphragm of this type in which, by reason of its use with cells of large capacity in 15 which the diaphragm is suspended from the means forming the gas chamber above the electrode, must have large surface area and possess sufficient tensile strength to resist distortion as a result of the dead load of the 20 diaphragm upon its points of suspension.

Diaphragms of the type to which my invention relates, are ordinarily formed of woven asbestos, the weave being sufficiently close to form a gas impervious barrier possessing sufficient porosity to ensure the absorption thereby of electrolyte in a cell. Such fabrics have little inherent strength, and when a considerable length and breadth thereof is required to form the diaphragm, 25 the constant stresses to which such diaphragms are subjected, as a result of the circulation of the electrolyte from adjacent the anode to adjacent the cathode, coupled with the dead load of the weight of the diaphragm, 30 have a tendency to stretch the diaphragm at some point thereof in a manner to attenuate or separate some of the strands of asbestos cord with which the diaphragm is made to an extent to form channels of sufficient 35 magnitude to permit the flowing electrolyte to carry gas bubbles from adjacent one electrode to adjacent the other while the cell with which the diaphragm is used is in operation. This likelihood of the formation 40 of openings in the diaphragm as a result of the distortion thereof from the causes above referred to, was developed only with the development of high amperage cells.

In order to permit the use of diaphragms 45 of woven asbestos or other similar material which is not subject to disintegration by contact with the diaphragm, I so construct the diaphragm that portions thereof only will be so reinforced as to have imparted thereto sufficient tensile strength to sustain the load 50 of the diaphragm without likelihood of its

stretching, these reinforcements being of the same material as, or a material similar to the body of the diaphragm, being so spaced in relation to each other as to cause a sufficient portion of the load of the diaphragm to be sustained thereby, while permitting intervening portions of the diaphragm to possess those characteristics which permit a free circulation of the electrolyte therethrough while preserving therein the necessary gas 60 impervious properties. In this manner stretching of the diaphragm is reduced to a minimum, as determined by the increased strength of these reinforced portions without materially effecting or modifying the total capacity of the diaphragm as to the passage of electrolyte therethrough.

In a measure, the reinforced portions of the diaphragm will also check a tendency of the fabric of the diaphragm to wrinkle or buckle during the assembling of the cell, which tendency is also resisted by providing the lower edge of the diaphragm with a substantially rigid reinforcement extending 70 about same. Since this reinforcement is carried by the diaphragm which is itself of non-conductive material, likelihood of short-circuiting through this stiffening or reinforcing member at the lower edge of the diaphragm is practically precluded, although preferably I enclose the reinforcing member in a bight or hem formed about this lower edge.

As a further safeguard against distortion 75 of the diaphragm, I form a tuck in the material thereof which extends circumferentially about the entire diaphragm intermediate the top and bottom thereof.

In a diaphragm embodying my invention, I preserve therein a sufficient measure of flexibility, while ensuring sufficient stability in the fabric of the diaphragm to avoid likelihood of the formation of openings therethrough with a resultant commingling of gases generated upon opposite sides of the diaphragm.

The invention consists primarily in a diaphragm embodying therein a woven textile sheet immune to deterioration from the action of the electrolyte thereon, said diaphragm having an open top by which it is adapted to be suspended, a face of said sheet having secured thereto vertically extending strips spaced apart with relation to each other, and formed of a textile material also immune to the action of the electrolyte; and

in such other novel features of construction and combination of parts as are hereinafter set forth and described, and more particularly pointed out in the claims hereto appended.

Referring to the drawings,

Fig. 1 is a side view of a diaphragm embodying my invention;

Fig. 2 is an end view thereof; and
10 Fig. 3 is a section on the line 3—3 of Fig. 1.

Like letters refer to like parts throughout the several views.

In the embodiment of my invention
15 shown in the drawings, *a* indicates a member forming a chamber adjacent the top of a cell for the reception of gas generated within the diaphragm.

The diaphragm proper consists of a sheet
20 of textile fabric extending entirely about and secured to the lower part of the member *a* so as to form a continuous barrier about an electrode supported within said diaphragm. In this manner the top and the bottom of the
25 diaphragm are both open so as to permit electrolyte to circulate freely through the open bottom thereof and permit the gas bubbles to escape freely through the open top thereof into the gas chamber above
30 same.

Ordinarily this diaphragm is made of woven asbestos fabric which is immune to substantial deterioration from the electrolyte within the cell.

35 With high amperage cells using electrodes of large surface area, it is essential to use diaphragms also having a large area and the dead weight of such diaphragms is sufficiently great to cause the stretching there-
40 of while the cell is in operation, with a re- sultant opening of interstices therethrough of sufficient magnitude to permit small gas bubbles to flow therethrough with the circu-
45 lation of the electrolyte from one side of the diaphragm to the other, as a result of pressure conditions developed during the decomposi-
50 tion of the electrolyte. Such stresses on the diaphragm are in a direction from adjacent the anode to adjacent the cells of high output capacity.

Since large diaphragms possess consider-
55 able inherent weight which is very much in- creased when saturated with the electrolyte, it is apparent that in mounting the dia-
phragms in or removing them from the structure of the cell, the likelihood of dis-
tortion is very great under such conditions, even though the diaphragm is secured to the
60 member *a* at closely adjacent points.

To avoid local disintegration of the dia-
phragm either while in use or while being assem-
bled in or removed from the cell, I provide reinforcements extending vertically
65 of the diaphragm, which will cause no ma-

terial reduction in the absorptive proper-
ties of the diaphragm and will afford points
of support spaced apart with relation to each other sufficiently to leave large areas of
the desired normal thickness of the dia-
phragm, while sustaining the main load of
the diaphragm at points having relatively
lower elasticity or stretch than the main por-
tion of the diaphragm.

In the accompanying drawings, the sheet
of asbestos fabric forming the diaphragm
is shown at *b*, while the vertically extend-
ing reinforcing strips which are preferably
formed of the same material, are shown at
70 *c*, the end reinforcing strips *c'* extending
across the ends of the diaphragm and be-
ing lapped over the adjacent side portions
thereof, since the additional thickness of the
diaphragm at this point will have no appre-
ciable effect upon the generation of the
gases by reason of the thinness of the edges
80 of the electrodes presented towards this por-
tion.

85 The strips *c*—*c'* may be secured to the
body sheet *a* in any desired manner as by
stitching, although any other desired fas-
tening means may be employed, since even
though of metal, such means being support-
ed by a body which is itself of non-conduct-
ing material, will have no tendency to short-
90 circuit the cell.

To avoid possible skewing of the sheet,
or a sagging thereof intermediate the rein-
forcements *c*—*c'*, I preferably loop the
diaphragm upon itself to form a tuck there-
100 in, which extends horizontally about the
diaphragm at a point intermediate the top
and bottom thereof and forms a horizon-
tally extending reinforcement *d*, this tuck
being formed before the application of the
105 reinforcing strips thereto.

At the bottom of the diaphragm, I prefer-
ably mount a rigid stiffening member or
reinforcement *e*, which member is envel-
oped in the material of the diaphragm sheet
110 so that it may, if desired, be of heavy metal
wire, since the materials of the diaphragm
sheet will serve as an insulation for this
bottom reinforcement.

The number and arrangement of strips
115 *c*—*c'* may be varied according to the sur-
face area of the diaphragm, as may also
their width, it being desired to limit the
number to as few as possible, in order that
the major portion of the diaphragm will
120 have a standard thickness which will facili-
tate the circulation of electrolyte there-
through, although the absorbent properties
and porosity of the reinforcing strips, both
vertical and longitudinal, will permit the
125 circulation of electrolyte therethrough with
but slight retardation.

While the diaphragm is in use, the rein-
forcements employed will prevent any sub-
stantial vertical stress in the fabric of the
130

sheet *b*, since the reinforcements *c*—*c'* will give sufficient support to the diaphragm at points adjacent thereto to ensure against stretch at such points, and the dead weight 5 of the diaphragm intermediate such reinforcements will be insufficient to cause material stretch at such intermediate point.

The horizontal reinforcement *d* will check any tendency of the diaphragm to stretch 10 by reason of the bulging of the portions thereof between the strips *c*—*c'*, or check any tendency of these portions to stretch by reason of a skewing action of the diaphragm.

The rigid reinforcement *e* at the bottom 15 of the diaphragm while supplementing the action of the reinforcement *d*, is provided mainly for the purpose of ensuring against the wrinkling or bunching in the diaphragm when assembling it in the cell.

20 It is not my intention to limit the invention to the precise details of construction shown in the accompanying drawings, it being apparent that such may be varied without departing from the spirit and scope of 25 the invention.

Having described the invention, what I claim as new and desire to have protected by Letters Patent, is:—

1. A diaphragm embodying therein a 30 woven textile sheet of material immune to deterioration from the action of electrolyte thereon and so formed as to completely enclose an electrode, and vertically extending strips secured upon a face thereof and spaced 35 apart with relation to each other, said strips being formed of a textile material immune to the action of electrolyte thereon, whereby said sheet may be suspended from adjacent the upper edge thereof about the diaphragm 40 without likelihood of the weight of the diaphragm distorting same so as to form openings of sufficient magnitude to permit gas bubbles to flow therethrough.

2. A diaphragm embodying therein a 45 woven textile sheet of material immune to deterioration from the action of electrolyte thereon and so formed as to completely enclose an electrode, and vertically extending strips secured upon a face thereof and spaced 50 apart with relation to each other, said strips being formed of a textile material immune to the action of electrolyte thereon, whereby said sheet may be suspended from adjacent the upper edge thereof about the diaphragm 55 without likelihood of the weight of the diaphragm distorting same so as to form openings of sufficient magnitude to permit gas bubbles to flow therethrough, said sheet being so formed as to present a continuous barrier about an electrode and to have an open top and an open bottom.

3. A diaphragm embodying therein a 60 woven textile sheet of material immune to deterioration from the action of electrolyte thereon and so formed as to completely enclose an electrode, and vertically extending strips secured at and extending across the opposite ends thereof, and lapping upon the sides adjacent each end, and upon opposite sides thereof at spaced intervals, said strips 65 being formed of a textile material immune to the action of electrolyte thereon, whereby said sheet may be suspended from adjacent the upper edge thereof about the diaphragm 70 without likelihood of the weight of the diaphragm distorting same so as to form openings of sufficient magnitude to permit gas bubbles to flow therethrough.

4. A diaphragm embodying therein a woven textile sheet of material immune to 80 deterioration from the action of electrolyte thereon and so formed as to completely enclose an electrode, and vertically extending strips secured at and extending across the opposite ends thereof, and lapping upon the 85 sides adjacent each end, and upon opposite sides thereof at spaced intervals, said strips being formed of a textile material immune to the action of electrolyte thereon, whereby said sheet may be suspended from adjacent the upper edge thereof about the diaphragm 90 without likelihood of the weight of the diaphragm distorting same so as to form openings of sufficient magnitude to permit gas bubbles to flow therethrough, said sheet being so formed as to prevent a continuous barrier about an electrode and to have an open top and an open bottom.

5. A diaphragm embodying therein a 95 woven textile sheet of material immune to deterioration from the action of electrolyte thereon and so formed as to completely enclose an electrode, vertically extending strips secured upon a face thereof and spaced apart 100 with relation to each other, said strips being formed of a textile material immune to the action of electrolyte thereon, whereby said sheet may be suspended from adjacent the upper edge thereof about the diaphragm 105 without likelihood of the weight of the diaphragm distorting same so as to form openings of sufficient magnitude to permit gas bubbles to flow therethrough, and a horizontal fold extending about the material of 110 the diaphragm.

6. A diaphragm embodying therein a 115 woven textile sheet of material immune to deterioration from the action of electrolyte thereon and so formed as to completely enclose an electrode, vertically extending strips secured upon a face thereof and spaced apart 120 with relation to each other, said strips being formed of a textile material immune to the action of electrolyte thereon, whereby said sheet may be suspended from adjacent the upper edge thereof about the diaphragm 125 without likelihood of the weight of the diaphragm distorting same so as to form openings of sufficient magnitude to permit gas bubbles to flow therethrough, said sheet be- 130

65 70 75 80 85 90 95 100 105 110 115 120 125 130

ing so formed as to present a continuous barrier about an electrode and to have an open top and an open bottom, and a rigid reinforcement extending about the lower 5 edge of the diaphragm.

7. A diaphragm embodying therein a woven textile sheet of material immune to deterioration from the action of electrolyte thereon and so formed as to completely enclose an electrode, vertically extending strips secured upon a face thereof and spaced apart with relation to each other, said strips being formed of a textile material immune to the action of electrolyte thereon, whereby said 10 sheet may be suspended from adjacent the upper edge thereof about the diaphragm without likelihood of the weight of the diaphragm distorting same so as to form openings of sufficient magnitude to permit gas 15 bubbles to flow therethrough, said sheet being so formed as to present a continuous barrier about an electrode and to have an open top and an open bottom, a hem being formed about the open bottom of said diaphragm, 20

and a metallic reinforcement enclosed by 25 said hem, whereby said reinforcement will have a non-conductive covering.

8. A diaphragm embodying therein a flexible absorbent body adapted to be interposed between electrodes of opposite polarity and adapted to be suspended from adjacent the upper edge thereof, and vertically extending strips of absorbent material secured upon a face thereof and spaced apart with relation to each other, whereby said 30 sheet is relieved from likelihood of distortion from the weight of the diaphragm, and the resultant formation of openings of sufficient magnitude to permit gas bubbles to 35 flow therethrough.

In witness whereof I have hereunto affixed my signature, in the presence of two subscribing witnesses, this 30th day of September 1921.

ISAAC H. LEVIN.
